United States Patent Office

Des. 225,353
Patented Dec. 5, 1972

225,353

MODEL RACING CAR

Eric Harrison Broadley, Pangborne, near Reading, England, assignor to Lola Cars Limited, Huntingdon, England

Filed July 2, 1971, Ser. No. 159,159

Claims priority, application Great Britain Jan. 5, 1971

Term of patent 3½ years

Int. Cl. D21—01

U.S. Cl. D34—15

FIG. 3

FIG. 4

FIG. 1 is a top plan view of a model racing car showing my new design;

FIG. 2 is a front elevational view thereof;

FIG. 3 is a left side elevational view thereof, the right side being substantially similar thereto; and

FIG. 4 is a rear elevational view thereof.

I claim:

The ornamental design for a model racing car, as shown and described.
